UNITED STATES PATENT OFFICE.

JOHN F. CRAIG, OF TOLEDO, OHIO.

EXPLOSIVE-ENGINE.

SPECIFICATION forming part of Letters Patent No. 644,004, dated February 20, 1900.

Application filed December 24, 1898. Serial No. 700,238. (No model.)

To all whom it may concern:

Be it known that I, JOHN F. CRAIG, a citizen of the United States, residing at Toledo, in the county of Lucas and State of Ohio, have 5 invented new and useful Improvements in Explosive-Engines, of which the following is a specification.

My invention relates to that class of balanced explosive-engines which embrace two 10 pistons movable toward and from each other in a single cylinder and connections between said pistons and the oppositely-disposed cranks of a common main or drive shaft.

It consists in a simple and compact construction especially adapted for use in boats, 15 motor-wagons, and the like and will be fully understood from the following description and claim when taken in conjunction with the annexed drawings, in which—

20 Figure 1 is a vertical diametrical section of my improved engine. Fig. 2 is a similar view taken in a plane at right angles to Fig. 1. Fig. 3 is a transverse section taken on broken line 3 3 of Fig. 2.

25 In the said drawings similar letters designate corresponding parts in all the views.

My improved engine is vertically disposed and its cylinder A is arranged upon and connected to a housing B, which is designed in 30 turn to be arranged upon and connected to a suitable bed or frame. (Not shown.) The cylinder, which is open at its opposite ends and surrounded by the usual water-jacket a, is provided adjacent to its upper end and at 35 diametrically-opposite points with longitudinal slots b. It is also provided at an intermediate point of its length with a port c, which connects its interior with that of a valve-casing C. This valve-casing has a gas-

40 inlet port d and an exhaust-port e and contains valves f g, the former being arranged to seat toward the port d, so as to control the admission of gas, and the latter to seat toward the port e, so as to control the discharge of 45 the products of combustion. The valve f is closed and kept normally closed by a spring h and is designed to be opened by the suction created in the cylinder incident to the discharge of the products of combustion.

50 The valve g is opened through the medium of a cam-tappet g', which is arranged to act against the lower end of its stem and is mount-

ed on a shaft g² and connected by gearing, as shown, with the main or drive shaft of the engine. Said valve g is closed and kept normally closed by a spring i, arranged as shown. The gearing intermediate of the shaft g² and the drive-shaft D comprises a gear-wheel g³ on shaft D, a gear-wheel g⁴ on a short shaft g⁵, mounted in the housing B, a sprocket-wheel g⁶, fixed on said shaft g⁵, a sprocket-wheel g⁷, fixed on the shaft g², and a sprocket-belt g⁸, connecting the wheels g⁶ g⁷.

D is the main or drive shaft of the engine, which is journaled in suitable bearings in opposite walls of the housing B and is provided with outer cranks j, disposed in one direction, and an intermediate crank k, disposed in an opposite direction, and E F are the upper and lower pistons, which are arranged to move in 70 the cylinder A. The lower of these pistons is connected by an interposed pitman l with the intermediate crank k of the shaft D, while the upper piston is fixedly connected to a cross-bar G, which extends through and is designed to move in and be guided against horizontal movement by the slots b of the cylinder. The portions of the bar G which extend laterally from the cylinder A are arranged above and in the same vertical planes 75 as tubes H, fixed to and located at opposite sides of the cylinder A. These tubes H are designed to receive and guide movable cross-heads I, which are connected by pitmen J to the outer cranks j of the shaft D and by rods 80 K to the extended portions of the bar G. The rods K are rigidly connected to the cross-bar G and cross-heads I, and as a result of the bar G being arranged in the guide-slots b and the cross-heads in the guide-tubes H it will 85 be seen that the cross-heads, the cross-bar, and the cylinder E will move smoothly in a straight line and will be free from any tendency to bind. It will also be observed that by reason of the cross-heads I being arranged 90 in the tubes H and said tubes communicating at their lower ends with the housing the cross-heads and the interior of the guide-tubes may be freely lubricated without spilling any lubricant around the engine, since 95 the drippings of lubricant will fall in the housing B. The arrangement of the cross-heads I in the tubes H is also advantageous, because it removes the liability of the cross-

head striking the person or catching into the clothing of the attendant or any other person standing close to the engine.

The explosion of the gas in the cylinder is effected by any suitable means, which I have not deemed it necessary to illustrate, when the pistons E and F are in the position shown in Fig. 2, and it serves to force said pistons in opposite directions and, through the medium 10 of the connections described, partially rotate the shaft D. The movements of the parts are so timed that when the pistons E F reach the end of their outer stroke the valve g is opened, with the result that the products of 15 combustion rush out through the opening e. Such discharge of the products of combustion continues until the pistons again reach the innermost ends of their strokes. At this time the valve g is closed, and as the pistons re- 20 cede from the center of the cylinder they create a vacuum which operates to unseat the valve f against the action of spring h, when the gases rush in through port d and past valve f. This inflow of gas continues inci- 25 dent to the outward movement of the pistons, and at the completion of such movement the valve f is closed by the pressure of the spring h, and on the subsequent inward stroke of the pistons the charge of gas in the cylinder is 30 compressed until the pistons reach the inner ends of their strokes, when another explosion takes place and the operation before de- 35 scribed is repeated. When the explosions take place, they force the pistons in opposite directions with the same impulse, and as the pistons have the same area they both carry

the same load, and the loads are transferred to the cranks, causing one crank to move toward the cylinder and the other or others to move away from the same with exactly the 40 same force. This balances the engine and does away with the excessive vibration so common in explosive-engines.

Having thus described my invention, what I claim is—

The herein-described explosive-engine comprising the housing, the upright cylinder, open at both ends, arranged upon, connected to and communicating directly with the housing having longitudinal slots at opposite points in 50 its upper portion, the upright guide-tubes located at opposite sides of and fixed to the cylinder and communicating at their lower ends with the housing and having their upper ends open, the shaft journaled in suitable bearings 55 in the housing and having cranks, lower and upper pistons arranged in the cylinder, a pitman connecting the lower piston and one crank, a cross-bar connected to the upper piston and extending through the slots of the 60 cylinder, cross-heads arranged in the guide-tubes and rigidly connected with the extended portions of the cross-bar, and pitmen connecting the cross-heads and cranks of the shaft, substantially as specified.

In testimony whereof I have hereunto set my hand in presence of two subscribing witnesses.

JOHN F. CRAIG.
